190,774

LIQUID DISPENSER FOR VEHICLE WINDSHIELD CLEANING

Robert R. Mandy, 7055 Fenkel Ave., Detroit, Mich.

Filed June 13, 1960, Ser. No. 60,940

Term of patent 14 years

(Cl. D58—17)

FIG. 1

FIG. 2

FIG. 3FIG. 4FIG. 5FIG. 6FIG. 1 is a front elevational view of a liquid dispenser for vehicle windshield cleaning showing my new design;

FIG. 2 is a front perspective view thereof looking toward one end;

FIG. 3 is a rear perspective view thereof looking toward the opposite end;

FIG. 4 is a top plan view thereof;

FIG. 5 is a bottom plan view thereof; and

FIG. 6 is a fragmentary vertical cross sectional view taken along the lines 6—6 in FIG. 5.

I claim:

The ornamental design for a liquid dispenser for vehicle windshield cleaning, as shown.
